(57) CLAIM

The ornamental design for a shoe, as shown and described.

DESCRIPTION

FIG. 1 is a front bottom perspective view of a shoe showing my new design;

FIG. 2 is a bottom view thereof; and,

FIG. 3 is a rear bottom perspective view thereof.

The broken line immediately adjacent to the photographic area defines a boundary of the claimed design and forms no part thereof. The broken lines depicting the remainder of the shoe form no part of the claimed design.
